Attorney

UNITED STATES PATENT OFFICE.

HAGOP J. YAGHUBIAN, OF NEW YORK, N. Y.

REVERSIBLE COAT.

Application filed December 8, 1922. Serial No. 605,601.

To all whom it may concern:

Be it known that I, HAGOP J. YAGHUBIAN, a citizen of Armenia, residing at New York, in the county of New York and State of New York, have invented certain new and useful Improvements in Reversible Coats, of which the following is a specification.

The invention has for an object to provide a coat which may be worn with either side presented outwardly, and therefore adapted to be made in a form for use in fair or rainy weather, with appropriate appearance and function. It is a special object of the invention to enable the production of such a coat in a form that will have a good set and appearance with either side turned outwardly. It is also a special object of the invention to enable the production of such a coat with all of the seams by which the inner and outer elements are joined stitched on the inside and concealed. A further important object of the invention, specifically is to provide a construction whereby the set of the shoulder, the cut of the sleeve and the upper back of the coat will be correct for both sides of the garment, no matter which is turned outwardly, and whereby the elements which is underneath will not interfere with the set of the outer one.

I am aware that attempts have been made to provide satisfactory coats of this character, and have observed that these are objectionable for the reason that one side or the other, when turned in will not function properly in co-relation with the outer element, and it is not possible to attain as good a fit as could be attained if a single coat corresponding to one side of the double garment were made. My invention, on the contrary, enables a coat to be produced which will have as good appearance as a single specially made coat of a like kind, with either side presented outwardly.

It is generally recognized that the fitting of sleeves on garments is an important element in the good appearance of style of a garment, and my invention enables a coat to be made in conformity with the strictest dictates of fashion. Other general and specific objects, advantages and features of invention reside in the method, form and assembled relation

of the elements, as will be more readily understood from the following description and accompanying drawings, wherein,

55

Figure 1 is a plan of the pattern for the front and back of the coat,

Fig. 2 is a similar view of the pattern for the sleeve,

Fig. 3 is a side elevation of the complete coat, with one side held so as to show the inner side of the garment,

Fig. 4 is a fragmentary detail of the sleeve,

Fig. 5 is a further detail of the sleeve and strap.

There is illustrated in Fig. 3 a coat representing one embodiment of the device as actually produced heretofore, in which a cheviot goods has been used upon one side, 70 and a cravenette serge upon the other. In the illustration, the serge is represented at 10 and the cheviot at 11 upon the inner side of the garment as shown. The inner side with the cheviot goods is utilized for fair 75 weather, while the cravenette serge is used for rainy weather. In the serge side straight pockets 12 are provided, while upon the side 11 of the coat patch pockets 13 are shown, the body of which is a little differently positioned, so that the contents of the two 80 pockets will not interfere or cause undue distortion of the coat when worn.

The coat as a whole comprises essentially two complete coat elements, either of which 85 may form the outside, while the other forms the lining, according to the way the coat is turned. The details of the patterns and other features of the coat, ordinarily, except with regard to the pockets, are identical. 90 The two coat elements are sewn together along the front and bottom edges, and the outer edges of the collar and lapel.

In order that the two coat elements may properly set without mutual disturbance, 95 some peculiarities of cut of the pattern has been found necessary, as well as a special method of manufacture in the stitching together of the elements. In the making of each coat element, the front 14 is cut to a 100 pattern as indicated in Fig. 1, by the lead arrows, and the back is cut on the pattern shown at 15. The sleeve patterns are shown in Fig. 2, the front and back elements 16

and 17, each requiring a special pattern which differ as represented, and are stitched together first at the edges which are shown in abutment in Fig. 2, and then at the outer edges. The edges 18 of the front and back 5 edges 14 and 15, are stitched together after which the sleeve, after the front and back are stitched together, is sewed to the recessed edge 18' of front and back, with the upper 10 end of the pieces 16 and 17 abutting the edges 19 and 20, and with the corners 21 and 22 of the parts 16 and 17 respectively, immediately abutting the corners 23 and 24 of the front and back at the top. The two 15 sides of one coat element being formed in this manner, they are stitched together at the back edge 25 and a collar 26, of which one-half is shown in Fig. 1 is then stitched to the top alined edge portion of the two 20 front pieces, the sleeve and the back.

It should be noted that the front sleeve at the piece 16 at the outer seam 27 is formed at that edge with a recessed part 28 extending from closely adjacent the elbow to adjacent the shoulder, while from just without the shoulder to the edge of the collar, it is formed with a convex edge 29, which extends over a distance of about 10 inches. The corresponding portion 30 of the back 30 member of the sleeve is formed with a slight convexity immediately adjacent the shoulder, this convexity, however, being much less than that 29 before mentioned. In 35 stitching these parts together, it is necessary to stretch the goods of one and to cramp the goods of the other, in the manner familiar in the art, with the result that a good shoulder conformation is attained without any elements which will tend to be conspicuous 40 by showing any irregularities of surface upon the outer part of the garment when it is worn, no matter which side is turned out. In making the elements 10 and 11, they are completed in the same manner 45 as they would for the application of a lining, the sleeves being similarly fitted, with the exception that no lining is in the sleeve separately, and the end edges 31 are left unhemmed and unattached, and a further 50 exception that a short slot is formed at 32 on the inner seam of the sleeve, formed by omitting the stitching between the parts 16 and 17, for a proper distance. Also, a large 55 opening or slot is left on the inner seam of the sleeve for a distance, as indicated at 33, in Fig. 2, in the seam of one of the elements 10 and 11 the side seams of the other sleeves being completed in every particular, except the slot 32. When the two coat elements are 60 to be put together, they are laid together with their right sides opposed and contacting, and the front edges 34, the bottom edges 35 and the outer edge 36 of the collar and the edges 37 of the lapel and collar ends 65 are stitched down upon a machine in the

usual way, and these may be finished in accordance with any practice approved, in the tailoring art. The edges of the goods immediately abutting the slot 32 may be turned back and pressed to form as the sleeves are 70 made, and should be carefully positioned for alinement of the slot in one sleeve with the slot in the corresponding sleeve which is joined therewith.

After attachment of the elements 10 and 11 as described, it should be noted that the sleeve of the two garments are then without any mutual connection, and also, customarily, I do not form cuff molds nor attach the sleeve straps 38 permanently, although, 80 if desired, it may be attached to the wrong side of one sleeve so that the strap will extend therefrom toward the outer side of the sleeve and toward the outer seam. The belt loop 39 may be attached where required before the elements 10 and 11 are connected. After stitching of the elements 10 and 11 together, as mentioned, the complete garment is drawn outwardly through one of the 85 openings 33 left in one of the sleeves, which it is found is readily practicable to accomplish, and this brings the right side of the goods of the elements 10 and 11 on the outer side, or facing away from each other. The connecting seams may then be pressed down 90 and given a front edge stitching 40 to impart the desired finish to the seam. The button holes are then cut and worked, care being taken to have the goods accurately laid when this is done. It should be noted 95 that in making the finished edge stitching 40 and in working the button holes, a thread is used at each side which matches the respective goods employed, one kind of thread being used in the shuttle and one on the feed 100 spool of the machine for making the seam 40, and similar thread being used for the working of the button hole 41 at each side, which is performed in separate operations 105 ordinarily. Buttons 42 are then secured 45 upon the coat, care being taken that the buttons on each side match the respective goods, and the buttons on one face are put directly opposite the buttons on the other.

After pulling of the two garment elements through the opening 33 of one sleeve, the sleeve on the two elements 10 and 11 at each side are adjusted carefully one within the other, and the outer end portions of the sleeves drawn outwardly through the slots 55 33 which have been left in one of each set of sleeves, and the outer edges 31 then stitched together, after which they may be thrust inwardly again through the opening 33 and the sleeve pressed to proper shape at 60 the end. The slots 32 will then be in position for accurate alinement, and the portion of each sleeve there adjacent will be unattached. The strap if not previously attached to one of the sleeves, may be then in. 65

serted through the slot 32 of the outer sleeve element and passed between the inner and outer sleeves a short distance, and then secured to the sides of the slots 32 on each sleeve, with suitably matched threads, being attached only at the same side of the slot in each sleeve, so that the opposite side of the slot in the two sleeve elements may be then stitched together. The completed double sleeve has then a slot passing therethrough immediately adjacent the base of the strap, so that the strap may be thrust through the slot to position the strap at either side as required. The strap is formed with material 10 on one side matching the element 10 and the material on the other matches the element 11, as may be understood. A belt 45 is provided, which also has material at opposite sides matching the respective elements 10 and 11. Buttons 46 are secured in accurate alinement with each other on both sides of the sleeve, spaced suitable distances from the slot 32, and preferably on the front piece 16 of the sleeve, in each instance; or so that 20 the strap may be extended over the front of the sleeve for attachment.

When the sleeve ends have been attached, the openings 33 may be closed by hand-stitching, of a fine order, and as this stitching is in a seam not readily seen, any slight imperfections will be in a position not likely to be observed. However, it is possible to perform this work so that it is practically invisible, if the thread is well matched and 25 of a small size.

If desired, different facings may be used upon the collar pieces 26 from the goods of either the elements 10 or 11, or this material may differ only on one side if desired.

The lapel 47 at one side of the double garment may be formed with button holes, and a button 48 provided on the front of the coat just under the collar on each side 45 and on each element 10 and 11. It should also be noted that button holes are formed in each side of the coat at the front edge, as shown in Fig. 3, and buttons also provided at each side and on each element 10 and 11 immediately inward of the button holes, so that the coat may be buttoned over 50 in either direction no matter which side of the garment is exposed outwardly.

In using the garment as described, when 55 worn with one of the elements 10 or 11 outside, and it is desired to reverse the garment, this may be readily accomplished by removal and turning the sleeves inside out. The belt is removed from the loop of the 60 first side presented outwardly, and readjusted through the loops on the side which is last required. The strap on the sleeve after turning will be found on the inner side of the sleeve, and it is simply inserted 65 through the slot 32 and drawn outwardly,

after which it may function as required, for a loose or tight fit, with the new adjustment.

It is an advantage of the method and structure employed that the coat may be manufactured by very simple operations 70 and very cheaply, because of the possibility of using the sewing machine on practically all of the seams, and in the attachment of the two elements 10 and 11, which makes it possible to put the garment out at a price 75 which will compare very favorably with the cost of ordinary overcoats of similar styles. It is also an advantage of the invention that the general style of the coat may be made to conform to various fashions in favor. It 80 should be noted that by the peculiar formation at 29 of the front element 16 of the sleeve, in conjunction with the simple form 30 of the back, the seam 27 is caused to aline centrally over the shoulder, extending 85 radially from the neck of the wearer, so that a good effect is presented when the garment is worn, in addition to the fact that the shoulder is given a good bulge causing it to conform snugly to the figure of the 90 wearer. This construction also obviates the number of seams required at the shoulder, lessening the liability of irregularities in contour by reason of the bulk of seams on the garment which have to be underneath 95 when the coat is worn.

What is claimed:—

1. The method of producing a garment of the character described consisting in making two complete garment elements including sleeves, with the exception of a turning slot in one sleeve at each side, sewing the two garment elements together at all boundary edges excepting the outer ends of the sleeves, drawing the two garment elements 100 outwardly through one of said turning slots completely, drawing mutually adjacent sleeve ends outward through the slot there adjacent, sewing the mutually adjacent sleeve ends together, thrusting them in 110 through the slots and then sewing up the slots.

2. In a coat, a sleeve having a front and a rear portion, said portions being curved at the upper outer edges, the radii of curvature 115 of said front and rear portions being different, and the length of the curved edge of the front portion greater than that of the corresponding edge of the rear portion, both edges being united to form a 120 seam by crowding the longer edge to the shorter edge for the purpose of having the outer seam formed by the junction of these two portions lie substantially on the median line of the arm as a prolongation of the 125 shoulder seam.

3. In a coat, a sleeve having a front and a rear portion, said portions being curved at the upper outer edges, the outer edge of the front portion having an edge that 130

curves outwardly at the upper part and then curves inwardly the length of the said edge of the front portion being greater than that of the corresponding edge of the rear portion, both edges being united to form a seam by crowding the longer edge to the shorter edge for the purpose of having the outer seam formed by the junction of these two portions lie substantially on the median line of the arm as a prolongation of the shoulder seam.

In testimony whereof I have affixed my signature.

HAGOP J. YAGHUBIAN.
